UNITED STATES PATENT OFFICE.

JOHN C. FARBER, OF WINDBER, PENNSYLVANIA.

METALLIC TIE.

1,249,940.

Specification of Letters Patent. Patented Dec. 11, 1917.

Application filed May 22, 1917. Serial No. 170,254.

To all whom it may concern:

Be it known that I, JOHN C. FARBER, of Windber, in the county of Somerset and State of Pennsylvania, have invented certain new and useful Improvements in Metallic Ties; and I do hereby declare the following to be a full, clear, and exact description of the invention, such as will enable others skilled in the art to which it appertains to make and use the same.

My invention relates to railroad ties and particularly to that class of metal ties which are used in connection with mining or surface trackage systems adapted to be moved about from place to place.

The object of the invention is to provide a simple and highly efficient tie effective for the usual purpose of maintaining the rails in proper alignment and including improved fastening elements fixed to the tie in such manner that the rail may be quickly placed in position and readily removed when the trackage is being transported.

In the accompanying drawing, Figure 1 is a view in perspective of my improved tie. Fig. 2 is an enlarged sectional view on line 2—2, Fig. 1. Fig. 3 is a plan view of a portion of the tie.

The tie, which is shown in the drawing in the form of a flat plate 1 having its edges beveled as at 2, is preferably laid directly upon the road bed, but if desired, may be used in conjunction with the common form of wooden tie or sleeper. The clamping means by which the rail is secured to the tie includes complementary rigid and movable members, the rigid member, 3, being riveted or otherwise secured to the tie. This member may be of any preferred form, such as a block with an overhanging flange 4 for engaging the base flange of the rail. The movable member of the clamping element is a short plate 5 held to, and preferably forming part of, the tie by a single bolt or rivet 6 which is placed about centrally of the length of the plate, such bolt forming a pivot for the plate. The plate is formed of resilient metal and one of its ends, 7, is slightly upturned to engage the base flange of the rail, the other end having means for holding the plate in normal position. I have shown this means as comprising a projection or stud 8 on the under face of the plate and adapted to take into a recess 9 in the tie, the projection or stud and recessed portion of the tie forming a locking means to pre-

vent turning of the plate on its pivot. That is to say, when the stud is out of engagement with its recess and rests upon the tie, the plate is bent as against its tension. When 60 the stud is seated in the recess the tendency is to hold it there.

To secure the maximum of efficiency in clamping the rail the end 7 of the plate has a straight edge 10 which, when the plate is 65 in normal engagement with the rail web, and the stud is in its recess, lies approximately parallel with the edge of the overhanging flange 4 of the rigid member 3 and with the web of the rail. The pivot 6 lies 70 approximately in a plane intersecting the transverse center of the edge 7 of the plate, thus insuring an equalized pressure of the clamp.

The plate 5 is usually placed adjacent the 75 side of the tie and the portion of the side of the plate in immediate juxtaposition to the web of the tie is cut away as at 12 so that in the clockwise turning movement of the plate there will be no interference between 80 the end 7 and the web of the rail, but the plate will be locked as against turning in the reverse direction.

In the usual construction, the fixed members 3 of the clamping means are on the outside of the rails, the movable members being placed on the inside. Each of the movable clamping plates is so located, on opposite sides of the tie, that its turning movement in a clockwise direction will permit 90 of disengagement of its projection 8 from the recessed portion of the tie and from the tie itself by a few strokes of a hammer or other implement.

In use the plate 1, with the fixed members 95 3 bolted or otherwise secured thereto, is laid on the roadway, with the movable clamping members 5 turned in the dotted line position indicated in Fig. 1. The rails are then trued after which the plate 5 may be readily 100 turned so as to lock the rail, the beveled edge 2 of the tie aiding in the movement of the stud over the edge and onto the tie, as this stud has been swung clear of the tie when plate 5 is free of the rail as shown in 105 dotted lines. The plate is locked by engagement of the stud 8 in the recess of the tie as the plate is turned to rail engaging position.

I claim as my invention:

1. In a metallic railroad tie, rail clamping 110 means including a fixed clamping block engaging one base flange of a rail, and a piv-

oted plate adapted to engage the other base flange, and means adapted to automatically effect a direct interlocking engagement between said plate and the tie as the former 5 is moved to rail engaging position.

2. A metallic railroad tie having a recessed portion, rail clamping means carried by said tie including fixed and movable clamping members, said movable clamping 10 means having a pivotal connection with said tie and a stud on its under face adapted to engage the recessed portion of said tie to normally prevent turning of said means.

3. A metallic railroad tie having a recessed portion, rail clamping means carried by said tie including a fixed clamping member and a plate pivoted to said tie, one end of said plate being adapted to engage the base flange of a rail and the other having 15 a downwardly extending stud adapted to interlock with the recessed portion of said tie 20

as the plate is moved to rail engaging position.

4. In a railway tie, the combination with a tie having a recess, and a fixed block 25 adapted to engage one base flange of a rail, of a plate pivotally mounted on said tie, said plate having an upturned end cut away at one side to permit of its turning in one direction and adapted to engage the other base 30 flange of the rail, said plate having a stud adapted to be normally seated in said recess and to be removed therefrom against the spring tension of said plate and to slide over the face of said tie when said plate is turned. 35

In testimony whereof, I have signed this specification in the presence of two subscribing witnesses.

JOHN C. FARBER.
